STRANDING MACHINE SPOOL CRADLE

Larry C. Frazier, Niles, Mich., assignor to National-Standard Company, Niles, Mich., a corporation of Michigan

Application November 10, 1949, Serial No. 126,648

6 Claims. (Cl. 57—1)

1

My present invention relates to stranding machines and more particularly to cradle means for supporting a spool of wire for machines of the character noted.

In stranding machines in use at present, it is the universal practice to provide cradle means in which a spool of wire is rotatably supported with its axis of rotation extending transversely of the axis of the cradle means. In such constructions the cradle means is journaled in a rotor means and in the design of such machines the axial length of the spool rotatably supported in the cradle means is a factor in determining the diameter of the rotor means. Thus, in known machines having a rotor means of small diameter, wire holding capacity of the spool is limited due to the short axial length of the spool. Increasing of the axial length of the spool to increase the capacity thereof results in unfavorable increasing of the diameter of the rotor means which, at high speeds, creates an undesirable centrifugal force problem.

I have conceived that the aforementioned and other disadvantages may be overcome and it is an object of my invention to do so by providing a cradle means in which a spool may be mounted so that its axis of rotation extends in the same direction as that of the cradle and preferably coaxial therewith.

It will be readily apparent that when mounting a spool in a cradle as above related, that the axial length of the spool does not become a factor in determining the diameter of the rotor means.

A preferred feature of my invention resides in providing a cradle means having a substantially hollow semi-cylindrical body defined by a thin shell and end walls; and in which the body portion of the cradle is only of slightly larger diameter than the spool diameter which enables construction of stranding machines with rotors of minimum diameter.

A further preferred feature is to provide a cradle as above noted having means for guiding wire withdrawn from a spool mounted therein substantially in the path of a helix.

A further preferred feature resides in providing a cradle, as last referred to, having means for imparting a tensioning action to the wire as it is unwound from the spool in the cradle.

A further preferred feature of one embodiment of my invention hereinafter disclosed, is to provide a cradle as aforesaid in which the means for guiding the wire in its helical path comprises a series of wire guide eyelets or the like, dis-

2

posed in a helical path in the body of the cradle, and in which the wire tensioning means is in the form of a dancer guide disposed at the wire exit guides of the cradle.

5 A further preferred feature of another embodiment of my invention is to provide a spool cradle having a flexible and hollow tube helically disposed in the body thereof and mounted at one end so as to lead the wire from the spool supported in the cradle out through one end of the cradle and with the other end of the flexible tube being free for approximately 90° of the cradle so as to impart the aforementioned spring tension action in the unwinding of the wire from 10 the spool in the cradle.

A further advantage of the aforementioned cradles as will presently appear, is that they may be readily adapted to either horizontal or vertical types of stranding machines.

15 The above and other objects, features and advantages of my invention will appear from the following detailed description of certain preferred embodiments of my invention.

20 Now in order to acquaint those skilled in the art with the manner of constructing and utilizing stranding machines and spool cradles in accordance with the principles of my present invention, I shall describe in connection with the accompanying drawings, certain preferred 25 embodiments of my invention:

25 In the drawings:

Figure 1 is a perspective view of one form of a cradle means for a stranding machine constructed in accordance with the principles 30 of my invention;

Figure 2 is a detail vertical sectional view of the dancer guide of the cradle of Figure 1, with the view being taken substantially along the line 2—2 of the latter view, looking in the 35 direction indicated by the arrows;

Figure 3 is a side elevational view, largely diagrammatic, of a stranding machine of the horizontal type, embodying the cradle means of Figure 1;

40 Figure 4 is a detail vertical sectional view taken along line 4—4, looking in the direction indicated by the arrows, and showing the manner of journaling an end of the cradle in the rotor;

Figure 5 is a perspective view of another form of 45 cradle means constructed in accordance with my present invention and which may be substituted for the cradle means of Figure 1 in the horizontal stranding machine of Figure 3;

Figure 6 is a perspective view of another form 50 of cradle means of my invention following in large

part the cradle means of Figure 1, but which additionally embodies a permanent magnet to adapt the cradle means for use in a vertical strander;

Figure 7 is a perspective view of another form of cradle means of my invention similar to that of Figure 6, but showing the permanent magnet mounted in a different position for adapting the cradle means for use in a vertical strander; and

Figure 8 is a side elevational view of a three wire vertical strander in which the cradle means of Figure 6 is mounted in the lower rotor, and in which the cradle means of Figure 7 is mounted in the upper rotor of the machine.

Referring now particularly to Figure 1 of the drawings, I have shown one form of cradle means, indicated generally at 5, constructed in accordance with my invention. The cradle 5 comprises end walls 6 and 7 which are joined by a thin semi-cylindrical wall 8 defining the body of the cradle. The end walls 6 and 7 are formed with end block-like portions 10 and 12, respectively. A cradle supporting shaft 13 is carried by the end block portion 10 and extends axially of the semi-cylindrical body portion 8. A hollow cradle supporting shaft 14 is carried by the block-like portion 12 and extends outwardly of end wall 7, axially of the semi-cylindrical body portion 8 and in axial alignment with shaft 13. The shafts 13 and 14 are formed with annular grooves 15 and 16 which receive hollow cylindrical rubber bushings 17 and 18, which provide for absorbing shock, and reducing vibration of the cradle when mounted in a stranding machine, as will later appear from the description of the manner in which the cradle is supported in a stranding machine.

The end block portions 10 and 12 are, as shown in Figure 1, formed with suitable openings or recesses 20 and 22 respectively, to provide for the journaling therein of the opposite ends of a spool shaft 23. In order for clarity of illustration, the end flange members for the spool supported by shaft 23 have been deleted from Figure 1 of the drawings, but it will be understood that such end flanges are provided and are adapted to be disposed closely adjacent the inner surfaces of the end walls 6 and 7. The spool, of which the shaft 23 forms a part, is detachably mounted in the end block-like portions 10 and 12 by means of releasable hairpin spring clips 25 which, as shown, are formed with linear legs 26 adapted to extend through openings formed in the legs 27 of each of the block-like portions 10 and 12. The hairpin spring clips 25 each further include a serpentine leg portion 28 for yieldingly retaining them in mounted position on the cradle, as shown in Figure 1. The spool shaft 23 adjacent each of its opposite ends, is formed with an annular groove 30 through which the straight leg portions 26 of the hairpin spring pins 25 extend to retain the spool in the cradle.

The cradle further comprises a series of metal wire guides or eyelets 32 arranged to lie in a substantially helical path in the shell 8 of the cradle so that the wire indicated at 35, carried by the spool mounted in the cradle, is caused to follow the helical path shown in withdrawing of the wire from the spool. At the end of the helical outlet path of the wire from the cradle the end wall 7 is suitably ported, as indicated at 35', to provide for the passage of the wire therethrough to the guiding wire member 36 of a dancer guide, indicated generally at 37. The dancer guide 37 as best shown in Figure 2, comprises a guide sleeve 38 threaded in the end wall 7 and in which the guide member 36 is mounted for reciprocation.

The guide member 36 has secured thereto a laterally projecting pin 39 which is adapted to have reciprocating movement in an elongated slot 40 in the guide sleeve 38, with the pin and slot serving to limit the upward and downward movement of the wire guide member 36. A coil spring 42 is arranged between the inner end of the member 36 and the bottom wall of a bore 43 formed in end wall 7. The spring 42 serves to support resiliently the member 36 in its reciprocation in the passage of wire through the eye of the wire guide member 36. From the dancer guide 37 the wire is guided through the end block-like portion 12 through a suitable passageway 45 formed therein and thence outwardly through the hollow shaft 14.

It will be observed that in the spool cradle above described, a spool of wire is adapted to be supported within the cradle, with the axis of the spool of wire extending coaxially of the axis of the cradle, so that wire is adapted to be withdrawn from the spool in a substantially helical path and through the dancer guide 37 which, as will presently appear, provides for effecting tensioning of the withdrawn wire.

Reference may now be had to Figure 3, in which I have shown a pair of spool cradles of the type described in connection with Figure 1, embodied in a horizontal machine. The machine shown in Figure 3 is largely conventional and comprises a rotor of known construction, indicated generally at 50, which is journalled for rotation at its opposite ends in bearing assemblies 52 and 53 carried in suitable supporting frame structures 54 and 55 respectively. An electric motor 56 is provided for driving the stranding machine and it has connection by an endless belt 57 to a drive pulley 58 fast to the end of the shaft 59 of the rotor 50 mounted in the end supporting frame structure 54. Upon energization of the electric motor 56, the rotor 50 is adapted to be rotated about a horizontal axis in its journalled support in the bearing assemblies 52 and 53.

The strander illustrated in Figure 3 is a three wire strander and comprises a tail spool, shown diagrammatically at 60, a second spool 61 and a third spool 62, with the spools 61 and 62 each being suitably supported in a cradle 5 of my invention. It will be understood that the showing of a three wire strander is illustrative only, since my invention may be embodied in machines having any desired number of spools. The tail spool 60 may be suitably supported in any appropriate and conventional manner and the wire 63 therefrom is adapted to be drawn through the stranding apparatus to be stranded with the wire 64 from the spool 61, and the wire 65 from the spool 62. At the end of the shaft of the rotor 50, supported in frame 55, a conventional stranding head, indicated generally at 66, is mounted for laying the wires 63, 64 and 65 over each other, and after which the laid wires pass through a closure die 67 from which the finished strand 68 extends to a bull wheel 69. The bull wheel 69 is driven in any suitable manner and three or four turns of the strand are wound thereabout so as to effect drawing of the several wires 63, 64 and 65 through the stranding apparatus. The finished strand 68 from the bull wheel, is wound on a strand spool in the conventional way.

My invention is concerned primarily with the arrangement of parts in which the spool cradle means 5 is journalled in the rotor 50 and of a spool in the spool cradle means, in view of which

the several structural details relating to the support of the tail spool, the journaling of the rotor in the supporting frame structure, the drive mechanism for the bull wheel and other elements of the stranding machine are not illustrated in detail since these are well known expedients in the art.

The end shafts 13 and 14 of each of the pair of cradles 5 are journalled in ball bearing assemblies supported in traverse frame members 10 which, in part, define the rotor 50. One of these ball bearing assemblies is shown at 71 in Figure 4 and it will be seen that the rubber bushing 17 of the end shaft 13 there shown, is disposed within the inner race member 12. It will be understood that the hollow end shaft 14 of the cradle 5 is mounted, likewise, in a bearing assembly so that the rubber bushings 17 and 18 provide a resilient mounting for the cradle. Thus, the shafts 13 and 14 are journalled in the rotor about an axis extending horizontally of the rotor so that the rotor may be rotated relative to the cradles 5 which, since their centers of gravity are disposed below the axis of the shafts 13 and 14, are restrained against rotation with the rotor 50 by the force of gravity. The journalled ends of the spool shafts 23 in the end block portions 10 and 12 permit rotation of the wire supply spools 61 and 62 so that these spools may rotate in withdrawing the wire therefrom.

The journalled shaft portion 59 of the rotor 20 is formed with a suitable bore through which wire 63 from the tail spool 60 passes. The wire 63 then extends laterally outwardly to known guide means for the rotor 50 so that the wire in travelling through the rotor 50 is rotated in a substantially cylindrical path. The wire 63 then passes laterally inwardly into and through a bore formed in the shaft portion of the rotor journalled in the bearing assembly 53 and thence to the stranding head 66. The wire 64 from the spool 61 is drawn through the wire guides 32 of the cradle 5 therefor, through dancer guide 37 and hollow shaft 14, then laterally outwardly and through suitable known guides of the rotor in a cylindrical path about the spool 62 and diametrically opposite wire 63, and thence laterally inwardly and through the end shaft of the rotor 50 journalled in the bearing assembly 23 to the stranding head. The wire 65 from the spool 62 passes outwardly through the hollow shaft 14 of the spool cradle therefor, through the adjacent journalled end of the shaft of the rotor 50 and to the stranding head 36 whereat the three wires are caused to be laid over each other as above related.

From the above description it will be observed further that the three wires drawn from the spools 60, 61 and 62 follow the conventional paths of conventional forms of stranding machines to effect the laying of the wires over each other to create a three wire strand.

Referring now to Figure 5, I have shown a modified form of cradle means indicated generally at 75 which is the same as the cradle means 5, except for the omission of the wire guide eyelets 32 and the dancer guide 37, and all other parts of the cradle 75, which are the same as those of cradle 5, are identified by the same reference numerals as used in describing cradle 5. In lieu of the wire guide eyelets 32 and the dancer guide 37, I propose to provide a wire guide and tensioning means in the form of a flexible metal tube 76 which, as shown, has one end thereof suitably secured to the block-like portion 12 in

the opening 45 therein which communicates with the hollow shaft 14, to provide for guiding a wire passing through the flexible tube outwardly through the hollow shaft 14. A plurality of clips 77 are provided for securing an intermediate portion of the flexible tube 76 in a substantially helical path adjacent the inside surface of the semi-cylindrical wall 8. The clips 77 are arranged so that the other end of the flexible tube is free and unconfined for approximately 90° of the body of the cradle. The free end of the flexible tube 76 is adapted to move axially to and fro of ends of a spool supported in the cradle and provides for applying a spring tension action to wire withdrawn from the spool which is carried by shaft 23, as previously described. The wire from the spool, after passage through the flexible tube 76, passes out through the hollow shaft 14 of the cradle. In all other respects, the cradle 75 is as described in connection with the cradle 5 of Figure 1, and the cradle 75 is adapted to be journalled in a rotor in the manner previously described in connection with the cradle 5. It will be readily appreciated therefore, that the cradle 75 may be substituted for the cradle 5 in the stranding machine of Figure 3 and that the flexible tube 76 serves to function to apply a spring tension action to the withdrawn wire from a spool mounted in the cradle 75.

Reference may now be had to Figure 8, wherein I have shown my invention embodied in a three wire vertical strander. A three wire vertical strander of the type illustrated in this figure is shown and described in detail in the application of Robert C. Pierce, Serial No. 107,675, filed July 30, 1949, to which reference may be had. The three wire strander shown in Figure 8 comprises an upper rotor indicated generally at 82, and a lower rotor indicated generally at 83. The upper rotor 82 provides for the journalled support of an upper cradle 84, shown in detail in Figure 7, and the lower rotor 83 provides for the journalled support of a lower cradle 85, as shown in detail in Figure 6. The cradles 84 and 85 are the same as the cradle 5, shown in Figure 1, but in addition the cradle 84 is provided with a permanent magnet 86, and the cradle 85 is provided with a permanent magnet 87. It will be observed that the upper cradle 84 has the permanent magnet 86 thereof secured to the block-like end portion 12 of the cradle, and that the lower cradle 85 has the permanent magnet 87 thereof suitably secured to the block-like end portion 10 of the cradle. The substantially square cross section of the end block-like portions 10 and 12 of the cradles provide for the convenient mounting thereon of the permanent magnets 86 and 87 so as to form unitary structures therewith. The purpose and function of the permanent magnets 86 and 87 will become apparent from the following description of the general elements making up the vertical strander shown in Figure 8. It will be understood that the strander shown in Figure 8 is largely diagrammatic and is only shown in detail insofar as an understanding of the application of the cradles of Figures 6 and 7 thereto is necessary.

In the vertical strander of Figure 8 a drive shaft, indicated at 90, has upper and lower positive drive pulleys 92 and 93 secured thereto. The drive shaft 90 may be driven by a suitable drive mechanism (not shown) for effecting rotation of the drive pulleys 92 and 93. The upper rotor 82 is journalled in suitable ball bearing assemblies, indicated generally at 96 and 97, which may

be supported in a forked shaped portion of the main frame structure (not shown) for the machine to provide for the support of the rotor. Likewise, the lower rotor 83 is also journalled in a pair of ball bearing assemblies 98 and 99 which similarly may be mounted in a forked shaped portion of the main frame structure. The main frame structure for the support of bearing assemblies for journalling of the upper and lower rotors 82 and 83 per se forms no part of my present invention, and in this connection reference may be had to the above referred to application. A positive drive pulley 100 is secured to the upper rotor 82 and is disposed between the bearing assemblies 96 and 97. A positive drive belt, indicated at 102 is trained over the pulleys 92 and 100 and provides for the positive rotation of the upper rotor 82 by the pulley 92 and drive shaft 90.

The lower rotor 83 has a positive drive pulley 103 secured thereto and disposed intermediate the bearing assemblies 98 and 99, and a drive belt 104 having positive drive teeth, is trained over the pulleys 93 and 103 to provide for positive driving of the lower rotor 83. As disclosed in the aforementioned application, the pulleys 92, 93, 100 and 103 are provided with teeth of gear form, and the endless belts 102 and 104 are formed with integral cleats or teeth which have positive driving connection with the teeth of the several pulleys referred to, so as to effect the positive drive of the upper and lower rotors 82 and 83. The pulleys 92 and 93 are of identical construction as are the pulleys 100 and 103 and which, together with the use of identical belts 102 and 104, provide for the synchronous rotation of the upper and lower rotors 82 and 83.

The vertical strander shown in Figure 8, as previously noted, is a three wire strander and includes a suitable tail spool 107; a spool 108 journalled in lower cradle 85, the shaft 13 of which is journalled in a ball bearing assembly in the lower rotor 83; and a spool 109 journalled in upper cradle 84, the shaft 14 of which, in turn, is journalled in a ball bearing assembly in the upper rotor 82. The wire 110 from the tail spool 107 passes through a bore in the lower rotor 83, then laterally outwardly in a cylindrical path to the upper rotor 82, then laterally inwardly and upwardly through the latter to the stranding head, indicated generally at 113, at the upper end of the upper rotor 82. A second wire 111 for the strand is drawn from the spool 108 through the wire guide eyelets 32, the dancer guide 37 and the upwardly extending hollow shaft 14 of the lower cradle 85 of the lower rotor 83 and is caused to follow a substantially cylindrical path about the upper spool cradle 84, journalled in the upper rotor 82, and thence to the stranding head. A third wire 112 is drawn from the spool 109, journalled in the upper spool cradle 84 of the upper rotor 82, through the wire guide eyelets 32, dancer guide 37 and thence upwardly through the upwardly extending hollow shaft 14 and an aligned bore in the shaft of the upper rotor 82 to the stranding head. The three wires 110, 111 and 112 are caused to be laid over each other in a conventional manner at the stranding head 113, as is well known in the art. As before, a bull wheel 115, driven in any suitable manner, is adapted to have three or four turns of strand wound thereon, whereby the bull wheel is adapted to draw the several wires 110, 111 and 112 from the spools described.

The upper cradle 84, as already noted, has the

hollow shaft 14 thereof journalled in the upper rotor 82 so that the latter may rotate relative thereto. In order to prevent rotation of the upper cradle 84, a pair of stationary permanent magnets 120 are supported by the main frame to lie in a plane in horizontal alignment with permanent magnet 86. The magnet 86 and magnets 120 are arranged with oppositely disposed pole faces and the gaps between the pole faces provide for the passage therebetween of the wires 110 and 111 at the upper end of their travel in the above mentioned cylindrical path.

The lower spool cradle 85, as before noted, is mounted in the lower rotor 83 by journalling of the shaft 13 therein so as to provide for rotation of the lower rotor 83 with respect of the cradle 85. As before, a pair of permanent magnets 122 are provided for cooperation with the permanent magnet 87 carried by cradle 85.

The stranding machine of Figure 8 further preferably comprises suitable light weight wire guide means which may comprise two pairs of parallel spokes, such as illustrated at 125, which may be arranged in diametrically opposed relation and suitably secured at their opposite ends to the upper and lower rotors to provide for guiding the wires 110 and 111 in their aforementioned cylindrical paths.

A spider 126, illustrated diagrammatically, connects the intermediate portions of the opposed pair of spokes 125 so as to prevent or restrain bowing outwardly of the spokes at their central portions in order to retain the wires 110 and 111 in a substantially true cylindrical path in passing to the stranding head. As before, the spools 108 and 109 are journalled in the cradles therefor, with their axes extending substantially coaxially of the axis of the shafts 13 and 14 of the upper and lower cradles.

Such features as the journalling of a spool at one end in a rotor, guide means such as defined by spokes 125, and other structural aspects of the strander of Figure 8, are not a part of my present invention, and for a further detail description of such parts, reference may be had to the aforementioned application of Robert C. Pierce. It is thought that for purposes of my present invention, the essential elements of a vertical strander as are necessary to an understanding of my present invention, are herein disclosed.

It will be readily understood that, if desired, the flexible tube 76 of the cradle shown in Figure 5 may be substituted for the wire guide eyelets 32 and dancer guides 37 of the cradles 84 and 85.

While I have shown and described what I consider to be certain preferred embodiments of my invention, it will be readily understood that various modifications and rearrangements may be made therein without departing from the spirit and scope of my invention.

I claim:

1. A spool cradle for a stranding machine having a substantially semicylindrical hollow body portion and end walls, and shaft means for journalling said cradle substantially coaxially of the axis of said body portion, means carried by said end walls for journalling a spool adapted to have a coil of wire thereon in said body portion substantially coaxially thereof, and wire guide means mounted on the inner periphery of said body portion and lying in a substantially helical path for guiding wire withdrawn from said spool along said path.

2. The spool cradle of claim 1 in which said wire guide means comprises a plurality of guide eyelets.

3. The spool cradle of claim 1 in which said wire guide means comprises a flexible metal tube.

4. The spool cradle of claim 1 characterized by the provision of dancer guide means mounted on the end wall thereof at the outer end of the helical path defined by said wire guide means.

5. The spool cradle of claim 1 characterized by the provision of rubber bushing means for said end shaft means to provide for the resilient mounting of the same in a stranding machine or the like.

6. The spool cradle of claim 1 in which said wire guide means comprises a flexible metal tube having a portion thereof lying substantially in said helical path for substantially 90° of said

body portion, one end of said flexible tube having connection with an opening formed in the end of said cradle means toward which the wire moves, and the other end of said flexible tube being free for travel to and fro axially of the coil of wire on said spool.

LARRY C. FRAZIER.
